UNITED STATES PATENT OFFICE

108,933

DESIGN FOR A PIANO CASE

Wilbur M. Day, Norwood, Ohio, assignor to The Baldwin Company, Cincinnati, Ohio

Application January 12, 1938, Serial No. 74,252

Term of patent 3½ years

To all whom it may concern:

Be it known that I, Wilbur M. Day, a citizen of the United States, residing at Norwood, in the county of Hamilton, and State of Ohio, have invented a new, original, and ornamental Design for a Piano Case, of which the following is a specification, reference being had to the accompanying drawing, forming part hereof.

The drawing is a perspective view of the piano case showing my new design.

I claim:

The ornamental design for a piano case, as shown.

WILBUR M. DAY.
